ATTORNEY

UNITED STATES PATENT OFFICE.

JOHN A. COREY, OF ROCKVILLE, RHODE ISLAND.

SAW-HANDLE.

SPECIFICATION forming part of Letters Patent No. 442,361, dated December 9, 1890.

Application filed November 20, 1889. Serial No. 331,020. (No model.)

To all whom it may concern:

Be it known that I, JOHN A. COREY, of Rockville, in the county of Washington and State of Rhode Island, have invented certain new and useful Improvements in Saw-Handles, of which the following, taken in connection with the accompanying drawings, is a specification.

This invention relates to that class of saws called "crosscut-saws," which are usually furnished with a handle at each end, and is an improvement upon my United States Patent No. 407,333.

The object of this invention is to make a strong inexpensive handle that can be easily, readily, and securely attached to the saw-blade when it is required for use and easily and quickly removed when not in use, and is fully illustrated in the accompanying drawings, making part hereof.

Figure 1 is a view of the handle. Fig. 2 represents a portion of the saw-blade with the openings for the studs of the handle to enter. Fig. 3 shows the position of the saw-blade and handle in putting them together. Fig. 4 is an end view of the lower end of the handle-plate, and Fig. 5 is an end view of the saw-blade. Fig. 6 shows a longitudinal section of part of the saw-blade, taken through the hole *f*.

The upper portion of the handle *D* is constructed in the usual shape, and preferably of wood, to the lower end of which a flat plate, preferably of metal, is attached, either by having a tang forged on its upper end to enter a hole in the wood or by a socket made in the upper end of said plate to receive the lower end of the wooden part of the handle. This lower plate part of the handle has a T-stud *a* riveted or otherwise firmly fastened to it, and another stud *b* is in like manner attached to the same plate nearer its upper edge. The T-stud *a* has an oval flat-topped head, with a neck of proper length to receive the thickness of the saw-blade.

The saw-blade *C*, Fig. 2, has two openings *f g* made through it near its end and at the same distance apart as the two studs *a b* are in the handle *D*. These openings *f g* are of

the same shape but slightly larger than the heads of the studs *a b*, so the latter when in right position will pass readily through them.

In Fig. 3 I have shown the mode of attaching the handle to the saw-blade. The handle is held horizontally to bring the head made oval in a direction transverse to the line of the handle of the T-stud *a* in the same vertical position as the oval hole *g* in the saw-blade is, and through which it is then passed, and the plate holding the stud is brought up close to the saw-blade, bringing the oval head of the stud *a* clean through the saw-blade. The handle is then turned up into the position shown by the dotted lines *D'* in Fig. 3, bringing the oval head of the stud in a transverse position to the oval hole *g*, so that it will not pull out. The stud *b*, as it passes the end of the saw-blade, springs it off (as the head of the T-stud prevents the two from entirely separating) sufficiently to allow it to pass, the edge of the saw-blade being beveled off (see *f'*, Fig. 5) to facilitate the operation, and when the stud *b* reaches the hole *f* it will spring in and hold the handle firmly from any change in position while the saw is worked back and forth in use.

The handle is removed, when desired, by springing off the saw-blade from the handle sufficiently to allow the stud *b* to be turned with the handle down to a horizontal position, when the T-stud can be removed from the opening *g*, and the handle will be clear from the saw-blade.

Having thus described this my improvement in saw-handles, I claim—

The combination of the handle *D*, with the oval-headed stud *a* and stud *b*, with the saw-blade *C*, having the opening *f* and oval opening *g* made therein, substantially as and for the purpose set forth.

In testimony whereof I have signed my name to this specification, in the presence of two subscribing witnesses, on this 12th day of November, A. D. 1889.

JOHN A. COREY.
